UNITED STATES PATENT OFFICE.

JOHN P. WEIS, OF NYACK, NEW YORK, ASSIGNOR OF ONE-HALF TO METROPOLITAN SEWING MACHINE CORPORATION, OF NYACK, NEW YORK, A CORPORATION OF DELAWARE.

TRANSMISSION MECHANISM FOR SEWING MACHINES.

Original application filed June 28, 1921, Serial No. 481,032. Divided and this application filed December 7, 1923. Serial No. 679,063.

To all whom it may concern:

Be it known that I, JOHN P. WEIS, a citizen of the United States, residing at Nyack, in the county of Rockland and State 5 of New York, have invented certain new and useful Improvements in Transmission Mechanism for Sewing Machines, of which the following is a specification.

This invention relates especially to improved transmission mechanism for the driving shaft of a machine, such as a sewing machine, and more particularly to improved stop clutch mechanism for controlling the rotation of the drive shaft so that 10 the shaft can be started and stopped at will and readily and efficiently controlled.

A further object of this invention is to provide improved mechanism for driving and transmitting power to the main shaft 20 of a machine which is adapted to be operated at very high speeds, and wherein the machine can be stopped and started instantly or as rapidly or slowly as desired without undue noise, shock or vibration and 25 wherein the improved construction requires a minimum amount of care, adjustment, replacement and oiling.

A further object of this invention is to provide a high speed automatic machine, 30 such as a sewing machine, having an improved drive or crank shaft construction for operating the various mechanisms of the machine, and having improved clutch mechanism for stopping and starting the shaft. 35 In the present instance the driving shaft comprises a detachable stop clutch section adapted to be readily detached from the main section of the shaft and removed to enable parts of the clutch mechanism to be 40 replaced or changed.

This application is a division of my co-pending application for sewing machines, filed June 28, 1921, Serial No. 481,032.

Other objects of this invention will appear in the following description and appended claims, reference being had to the accompanying drawings forming a part of the specification wherein like reference characters indicate corresponding parts in the 45 several views and wherein Fig. 1 is a side elevation of the machine with the end cap or

cover of the looper mechanism shown in dotted lines, and the transmitter shown in operating position under the machine, but detached from the work table to more clearly illustrate the relation of the transmitter with the sewing machine; Fig. 2 is a top plan view of the transmitter shown in Fig. 1; Fig. 3 is a front perspective view of the sewing machine, transmitter and treadle 55 connected for operating the same; Fig. 4 is a perspective view of the hand wheel and its shaft having clutch teeth in the end for turning the mechanism of the machine by hand; Fig. 5 is a back elevation of the 60 machine, illustrating the connections for the needle drive and a portion of the looper and feed actuating mechanisms; Fig. 6 is a perspective view showing the inside wall of the back cover plate with the stop motion 65 lever and its connecting parts assembled thereto; Fig. 7 is a vertical section taken through the vertical center line of the crank shaft bearing, showing the crank shaft, the 70 assemblage of the clutch wheel with a portion of the stop motion mechanism, the clutch hand wheel for turning the mechanism of the machine by hand, the frame of the machine being represented by broken lines; Fig. 8 is a transverse section taken substantially on line 8-8 of Fig. 7, and shows 75 particularly the stop clutch balls in a clutched position; Fig. 9 is a view similar to Fig. 8, but shows the stop clutch balls in a non-clutching position; Fig. 10 is a 80 detail view of the collar which forms a retainer for the clutch spring; Fig. 11 is a fragmentary perspective view of a portion of the crank shaft and stop clutch shaft; Fig. 12 is a detail plan view of the stop 85 lever, showing its mounting in the cover plate and machine frame, the latter being shown in broken lines; Fig. 13 is a side elevation of the stop lever shown in Figs. 6 and 12, the actuating rod therefor, the 90 stop clutch brake shoe and brake shoe lever being shown in full lines, and the frame in broken lines; and Fig. 14 is a sectional detail view of the actuating rod for the 95 stop mechanism, taken on lines 14-14 of 100 Fig. 13.

Before explaining in detail the present

improvement and mode of operation thereof, I desire to have it understood that the invention is not limited to the details of construction and arrangement of parts which are illustrated in the accompanying drawings, since the invention is capable of other embodiment, and that the phraseology which I employ is for the purpose of description and not of limitation.

Referring particularly to Figures 1, 3, 5, 7, and 13, it will be seen that the present machine is mounted on a suitable table 1 and comprises a machine frame of special construction having flanges 2 and 3 for supporting and securing the machine to the table. The main portion of the frame is preferably of hollow rectangular construction, closed at the bottom and having a front wall 4, and a rear wall 5 provided with an opening 6 adapted to be closed by a cover plate 7 attached thereto in any suitable manner. This cover plate has a hollow projection 8 within which operates a stop lever 118. The outline or shape of the opening 6 is irregular in form and is indicated at 6^a, 6^b, 6^c, 6^d, 6^e, and 6^f, Figure 5, the cover plate 7 being of similar form and adapted when closed seal the opening against leakage of oil.

As shown in Figure 13 the rear wall 5 is inclined to the left of the perpendicular, an advantage thereof being to assist in properly conducting the lubricant from one interior part to another and to finally conduct it into the reservoir formed by the bottom 9 and side walls 4, 5, 13, and 16 of the frame. To empty the reservoir I provide a drain pipe 10 tapped into the bottom 9. The front wall 4 is provided with a boss 11, bored to receive the cylinder 12. The side wall 13 is provided with a boss 14 to receive one of the crank shaft bushings 15. The opposite side wall 16 has a projecting rib 17 parallel to the wall 4, curved at 18, and provided with two bosses 19, the rib extending down the opposite side, parallel to the rear wall 5 as at 20, Figure 13.

Located on the side wall 16 near the bottom is a boss 21, forming together with the bosses 19 a suitable seat for the belt guard 22 which covers the drive belt 23, and the clutch and pump wheels 93 and 425.

The side wall 16 has a rectangular opening 24 into which projects the laterally extending portion 118^a of the stop lever, Figure 12, this opening also affording a passage for the lubricant returning from the outer bearing 25 of the bushing 99 carried by the belt guard 22, Figures 5 and 7. Above the opening 24 in the side wall 16 is an inwardly projecting boss 26 bored to receive bushings 101 and 101^a for supporting the crank shaft. The top portion of the frame carrying the boss 26 is indicated at 27 and the top wall of the frame at 28, Figure 7, wherein the

driving means and oil distributing reservoir is located. Projecting inwardly from the front wall is a boss 29 also bored to receive a bushing 29^a for supporting the crank shaft. Adjacent to the bottom 9 of the frame, and located in the side wall 16 is an inwardly projecting boss 30 bored to receive a pump casing 31.

Projecting from the wall 4 is an overhanging arm 32 terminating in the needle bar and presser bar bearings 33. Above these bearings is a rectangular opening 34 through which the presser spring and lifter lever operate. This overhanging arm 32 is provided with suitable bearings 37 and 38 for the needle operating rock shaft 39. By means of suitable connections fully described in my above mentioned application the rock shaft 39 is connected to the needle bar 48 which reciprocates in bearings 33. The needle bar 48 is hollow and the lower end is tapped to receive a needle holder 50 which carries needles 51. The rear end of the rock shaft 39 is connected to the upper end of a ball connection 59, the lower end 60 of which having a ball socket fitting over the ball 61 of the crank shaft.

With reference particularly to Figures 5, 10, 11 and 7, the crank shaft comprises bearing portions 62 and 63, the bearing 62 being integral with the crank disc 64 and the ball 61. The crank 65 is integral with the ball 61 and the portion of the shaft 63, the crank shaft 66 is also integral with the shaft portion 63 and with a ball 67, and the crank disc 68 is integral with balls 67 and 69, the latter forming a part of the shaft portion 70, shown in section in Fig. 7. The end portion 62 of the crank shaft is provided with a series of clutch teeth 72 to co-act with other clutch teeth 73 carried by a stub shaft 74 secured to a hand wheel 75 adapted for the purpose of turning the crank shaft and operating the mechanism of the machine by hand, if desired the shaft 74 is provided with a reduced neck 76 for the reception of the coiled spring 77 carried in the annular groove 78 of the bushing 15. The position of the spring with respect to the shaft neck 76 is such as to normally hold the clutch teeth 73 out of engagement with the clutch teeth 72, the contraction of the spring on the edge 79 of the neck tending to draw the shaft outward. Thus when the hand wheel 75 is forced inward by the hand of the operator to engage the clutch teeth for turning the shaft, the spring 77 is forced out of the neck and is expanded so as to cause the same to embrace the edge 79. When the inward pressure of the hand upon the wheel is removed, the contraction of the spring draws the shaft to a position where the spring enters the neck 76, disengaging the clutch teeth, and thus preventing the wheel from rotating during the operation of the machine.

From the foregoing it will be understood that I have provided a means, in the form of a hand clutch wheel whereby the mechanism of the machine may be readily turned by hand, such means being easily detachable from the machine by withdrawing the same as illustrated in Fig. 4. This feature is of considerable importance as it avoids the rotating of the hand wheel each time the machine is started, thus saving considerable power, and obviating the necessity of stopping the wheel since the same in the present machine is disconnected from the shaft at the time of starting and stopping and during the operation of the machine. In order to quickly start and stop a mechanism that is operated at a high speed such as three or four thousand revolutions per minute, all unnecessary weight and bulk of rotary parts must be eliminated. An important advantage of this improved machine resides in the elimination of the weight of the usual hand wheel in operation and the centrifugal force set up thereby, whereas if the wheel were directly connected to the shaft it would be very difficult, if not impossible, to bring the parts operating at such high speeds to a dead stop instantly, without excessive wear and tear on the mechanism.

The usual sewing machine is provided with a hand wheel which is grasped by the hand of the operator at the end of each stitching operation. The wheel is then turned to raise the needle to a position of rest to permit the removal of the work. This continuous stopping and turning of the hand wheel during the rapid operation of the machine becomes a laborious task, as it must often be repeated thousands of times daily, thereby consuming a considerable part of the operator's time. In many instances ten to twenty percent of the time consumed in stitching operations is spent in manipulating the hand wheel. In the present machine this stopping of the machine and turning of the wheel by hand to bring the needle at rest in its highest position is obviated by virtue of the provision of a positive stop motion, in the present instance the same embodying certain improvements over my Patent No. 1,352,333 dated September 7, 1920. A detailed description of these stop motion parts is deemed unnecessary since the same are fully described in the aforesaid patent.

Referring particularly to Figs. 5, 6, 7, 10, 11, 12 and 13, it will be seen that the portion of the shaft 70 is drilled at 80 to receive the reduced end 71 of the stop clutch shaft. A portion of the shaft extension 70 is enlarged to form the semi-circular key-way 81 which extends the entire length of the hole 80 and receives a semi-circular key 82 formed as an integral part of the reduced portion 71 of the stop clutch shaft. The telescoping of these parts provides a convenient way of

connecting the parts for quick coupling and uncoupling, as it is necessary at times to withdraw the stop clutch shaft in order to renew the wedge blocks 83 hereinafter described, or other parts.

Adjacent to the end portion 70 of the crank shaft, and between the faces of the bushings 101^a and 101, is located a collar 86 provided with a hole 87^a, and a key way 87^a, adapted to receive and embrace the end 71 of the stop clutch shaft for rotary movement therewith. The bushing 101 is recessed to receive the collar 86 so that the faces of the two bushings are flush with each other, thereby limiting the movement of the collar. A coil spring 87 is carried in a groove 88 terminating at 87^c on one side of the center line of the shaft hole 87^a, see Figure 10, and on the other side terminating at 87^b. The groove has two openings 87^e and 87^f through the rear wall of the collar 86, and through these openings the end of the spring 87 may be seen when assembling the parts, as one end of the spring abuts against the end 87^c while the other end exerts pressure against a pin 89 projecting through the opening 87^e and secured to and carried by a rockable stop clutch sleeve 90.

The stop clutch sleeve 90 is bored to fit over the reduced end portion 71 of the stop clutch shaft and such bore is also provided with a semi-circular key-way to fit over the semi-circular key 82. The enlarged section 85 of the stop clutch shaft is provided with three radially disposed pockets 84 into which are loosely seated segmental wedge blocks 83 which receive wedge balls 91. The sleeve 90 is bored to fit over the enlarged portion 85 of the stop clutch shaft, and such portion is provided with three apertures, each of which carries a ball 91. The key-way of the sleeve being larger than the key permits the sleeve 90 to be rocked on the shaft by spring 87, as hereinafter described, sufficiently to cause the three balls 91 to shift from a low non-clutching position on the wedge blocks 83 as illustrated in Fig. 9, to a clutching position where the balls are projected outwardly to grip the ball race 92 carried by the clutch or driving wheel 93, as illustrated in Fig. 8. The clutch wheel 93 is provided with a belt groove 94, and is made in two sections having respectively hubs 95 and 96. The hub 95 operates in the bearing 97 while the hub 96 operates in the bearing 98, so that the pull of the belt on the wheel 93 is taken up by these two bearings. The bearing 97 is formed in the bushing 99, carried by the boss 100 of the belt guard 22, and also forms an end bearing for the enlarged end portion 85 of the stop clutch shaft. One end portion of the stop clutch sleeve 90 extends into the hubs 96 and 95 of the clutch wheel and the opposite end portion thereof has a bearing in the bush-

ing 101, supported in the boss 26 of the machine frame. This bearing is also in the form of a bushing and is provided with a cut-out 102 which extends up from the bottom for the entrance of a stop finger. This cut-out registers with an eccentrically formed stop tooth 103, (see Fig. 13) formed in the clutch sleeve 90. Directly above the cut-out or opening 102 is located a brake shoe 104 which operates in an opening 105 at the top of the bushing 101 against the stop clutch sleeve 90. A spring 106 is carried between a screw collar 108 and a shoulder 109 of a presser plug 107, and exerts 10 downward pressure thereon, the shoulder 109 resting directly on the brake shoe.

The opposed surfaces of the presser plug and brake shoe are cut out forming a space between them to receive the free end 110 of the brake lifting lever 111 adapted to rock on a stud screw 112. The free end of the brake lifting lever 111 is provided with a segmental or arcuate face 113 centered substantially at 114, Figure 13. Co-acting 23 with the curved surface 113 is an anti-friction roller 115, secured by a shoulder screw 116, to an upstanding arm or projecting member 117 of a stop lever 118, mounted on conical screws 119 tapped into the side wall 30 of the projecting portion 8 for pivotally supporting the stop lever 118, the screws 119 forming a fulcrum for the stop lever. A stop finger 120 is connected by a joint pin 121 to the free end of the stop lever, the upper end 122 co-acting with the stop clutch tooth 103, and the lower end 123 co-acting 35 with the oil buffer indicated generally at 124 which is supplied with oil from a reservoir 125, formed as a part of the stop lever.

To overcome the falling weight of the free end of the stop lever 118, a spring 126 attached at one end 127 to the inside wall of the cover plate 7 is secured as at 128 to the stop lever, and normally urges the end 122 of the stop finger into engagement or co-action with the stop clutch tooth 103. From a consideration of Figs. 12 and 14 it will be seen that the stop lever 118 is provided with a rectangular opening 129, within which is pivotally secured a sleeve 130 by screws 131 and 132. The reduced end 132^a of the screw 132 is somewhat longer than the reduced end 131^a of the screw 131 55 so as to project through the wall of the sleeve and ride freely against the flattened face 133 of the push and pull rod 134, so that the end of the screw may engage the shoulder 135 of the flattened face 133 upon the predetermined downward travel of the rod.

The lower end of the rod 134 is connected as at 138 to an extension 137 passing through a guide aperture in the flange 3 and also through the work table 1, see Fig. 1,

and is freely and slidably held in an elongated slot 140 formed in the end of a lever 139 of the power transmitter by virtue of collars 141 and 142. Thus free up and down movement of the rod 137 in conjunction with lever 139 is obtained, the slot 140 permitting the necessary play or lost motion between the parts.

Referring particularly to Figs. 1, 2 and 3 it will be seen that the power transmitter consists of a main bracket 143 secured to the under surface of the table 1 in any suitable manner, the bracket having an arm bored to receive a shaft 144. Upon this shaft is mounted a cone pulley 145 over which operates the belt 146 for transmitting power from any suitable line shaft to the pulley. This pulley 145 is provided with a frictional surface 147, co-acting with a similar frictional surface 148 of the driven pulley 149 also carried by the shaft 144. The belt 23 is driven by the pulley 149 for operating the sewing machine. A bracketed lever 150 is carried by the rock shaft 151 supported in the arm 152 for rocking movement, and the forwardly projecting end 153 of the lever 150 has a suitable angular or camming face adapted upon rocking the lever inwardly to exert inward pressure on the cone pulley 145 thereby to force the frictional surfaces 147 and 148 together so as to clutch the pulleys 145 and 149 for rotation.

The shaft 151 has rockably supported thereon at 154 the lever 139, provided with a stud 155 to which is connected the upper end of a rod 156, the lower end being connected by a coupling 157 to a rod 158 connected to a floor treadle 159, whereby the transmitter may be operated in order to control the speed of the machine.

A brake lever 161 is also secured to the shaft 151, and the arm 152 is provided with a lug 162 having a spring 163 interposed between it and a lug 164 carried by the brake lever 161. The latter is provided with a frictional surface 165 to engage the rim 166 of the pulley 149 in order to quickly stop the pulley each time the rod 156 is thrust upward to shut off the power. Attached to the bracket 143 is a projecting member 167 carrying a stud shaft 168 upon which rotates an idler pulley 169, which directs the upward run 170 of the belt 23 to the clutch wheel 93.

For regulating the speed of the pulley 149 and the speed of the sewing machine an adjusting screw 171 and lock nut 172 is provided, the screw being tapped into the lever 139 as shown in Figs. 1, 2 and 3. The inner end of the screw engages the lever 150 and by adjusting the screw 171 inwardly the frictional surfaces 147 and 148 are brought together with greater pressure so that in

creased speed is obtained. By reversing the adjustment the pressure on the frictional surfaces is decreased and slippage results so that the speed of the pulley 149 and the sewing machine is thereby reduced. This speed regulation is of great importance when operating upon difficult work, and particularly when an inexperienced operator is at the machine, inasmuch as without a speed 10 regulator the machine is liable to start at the highest speed and the operator would lose control of the work. With the present improvement the requisite speed may be had by simple adjustment of the parts described to suit the desired or necessary conditions.

The lever 150 and the brake lever 161 are secured to the rock shaft 151 and hence a downward pressure of the rod 156 swings 20 the brake lever 161 away from the rim 166 somewhat before the frictional surfaces are brought firmly together. A reverse action of the rod 156 of course causes the frictional surfaces to separate prior to the effective operation of the brake lever 161 against the rim 166. Thus when the treadle is pushed down and the outer end of the lever 139 is shifted downwardly, the pulleys 145 and 149 will be 25 clutched together thereby causing the transmitter to impart movement to the belt 23 in the direction of the arrows shown in Fig. 1, so as to rotate the clutch wheel 93. This operation will take place prior to any actuation of the stop lever 118 by virtue of the fact that during the initial downward movement of rod 134 the screw 132^a rides in the 30 groove or flat surface 133. Upon a further downward movement of the foot treadle and the rod 156 connected therewith, the push 35 and pull rod 134—137 will be shifted downwardly to a position where the shoulder 135 will strike the screw 132^a and swing the lever 118 downwardly on the pivots 119 thereby shifting the stop finger 122 out of engagement with the clutch tooth 103. Simultaneously with this movement the roller 115 which is normally at rest above and out of 40 contact with the brake lifting lever 111, is shifted into engagement with the corner 115^a of the lever, thereby swinging the lever on the stud screw 112, lifting the pressure plug 45 107 slightly against the tension of the spring 106, and releasing the friction of the brake shoe 104 on the sleeve 90. This operation permits the spring 87 which is under tension 50 to rock the sleeve 90 relatively to the shaft 71, thereby shifting the balls 91 into a clutching position, at which time the crank 55 shaft is caused to rotate to start the machine.

It has been found in practice that whereas in the present case the machine is controlled from the treadle 159 by the operator's foot, and where the brake or pressure plug lifting lever 111 and stop lever 118 are constructed 60 substantially as in my aforesaid Patent

#1,352,333, breakage of certain of the parts, particularly the lifting lever, often occurs due to the accidental shifting of the stop lever too far downward—such being ordinarily impossible when the same is mechanically and automatically controlled. Therefore in order to avoid such disadvantages, the lifting lever 111 in the present instance is provided with the segmental portion 113 concentric with the plane of movement of the roller 115 about the pivotal axis of the stop lever. The stop lever is furthermore operated by the rod 134 intermediate the stop finger and the fulcrum 119 (Fig. 13) thereby facilitating a positive operation and greater compactness of structure. Thus after the roller, as hereinbefore stated, engages the corner 115^a to shift or swing the lever 111 downwardly during any further downward movement of the stop lever 118 the roller 115 will merely travel over the curved surface 113 thus maintaining the lever 111 in a constant position without any further swinging movement thereof.

From the foregoing it will be understood that the speed regulator 171 not only provides a means for controlling the speed at which the machine is operated, but also, under one adjustment provides a means whereby the stop finger 122 may be brought out of engagement with the stop tooth 103 before the clutch wheel 93 is caused to rotate, or before the clutch wheel attains its maximum speed. Under another adjustment the clutch wheel may be caused to rotate at high speed before the stop finger 122 is brought out of engagement with the stop tooth 103. In such case the machine will start instantly at maximum speed, whereas under the other adjustments the machine will start gradually at varying speeds until it reaches the maximum speed. Thus it will be seen that I have provided a means for varying the speed of the machine from the minimum to the maximum for controlling the speed at which the machine is started and stopped and for starting and stopping instantaneously at any speed without shock.

Although the power transmitter herein shown and described in connection with the present improved machine is a desirable preferred operating instrumentality, it is of course understood that any other transmission may be used without departing from the spirit of the invention, or if desired under the particular circumstances the clutch wheel may be operated direct from a line shaft. In that case the clutch wheel will be in constant operation and the machine when started will always operate at a predetermined speed.

It will be noted in the present machine that the rod 134 is utilized not only for operating the transmitter and the clutch mechanism thereof, as well as the stop mech- 130

anism for the crank shaft but also to lift the presser foot 188 of the machine. The upper end of 136 of this rod is adapted to engage the free end 177 of a rock lever 174 which is pivoted at 175 to a bracket 176. The opposite end 178 of this rock lever overhangs the rear end 179 of the presser foot lifting lever 180 which is pivoted at 181 to the overhanging arm 32 of the machine frame. The opposite end of the presser foot lifting lever extends through an opening 34 in the bearing 33 and is connected to the presser bar 183 which is adapted to reciprocate in a bushing 187 carried by the bearing 33. The construction and operation of this mechanism is fully described in my aforesaid application and therefore a further description thereof is not deemed necessary herein.

20 It will be noted that by making the crank shaft in two sections so that the stop clutch shaft is separate and detachable from the main crank shaft, an important advantage is derived over a construction wherein the shaft is made as one part. By virtue of this improvement the necessity of removing many parts is avoided when changing or replacing the cam block, and as a result no skill is required merely to remove the bushing 99 and draw the stop clutch shaft outward with the fingers. Thus the changing of the cam block and re-assemblage is quickly accomplished, as all other parts are so arranged as to remain in their working position while the shaft is removed or being replaced. A groove or slot 84^a is provided in the enlarged section 85 of the stop clutch shaft in order to provide clearance of the wedge balls 91 when withdrawing the shaft section 85.

40 It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use.

I claim:

55 1. The combination of a rotary shaft, means for transmitting power thereto and including clutch mechanism for stopping and starting said shaft, said clutch mechanism including a driven clutch member, a movable stop cooperating with said clutch member to engage and disengage the clutch mechanism, means for controlling the operative movement of said stop, said shaft having at its end a detachable section connected thereto for rotation, and a detachable bearing for said section to permit removal thereof.

2. The combination of a driven shaft, means including clutch mechanism for stopping and starting said shaft, said clutch mechanism including a driven clutch member adapted to be connected to said shaft, a movable stop cooperating with said driven clutch member to engage and disengage the clutch mechanism, means for controlling the operative movement of said stop, said shaft terminating at one end in a removable section cooperating with said clutch mechanism and shiftable relatively thereto, and a detachable end bearing for said section to permit removal thereof.

3. The combination of a supporting frame, a rotary shaft comprising a main portion and a detachable end section connected together for rotary movement, an end bearing carried by said frame within which is journaled said detachable section, said bearing being detachable to permit removal of said section, and stop clutch mechanism for stopping and starting said shaft.

4. The combination of a pair of connected shafts located in alinement and one thereof comprising a detachable clutch shaft, clutch mechanism for starting and stopping said shafts and including a driving clutch member and a driven clutch member, shiftable gripping means cooperating with said members, and means for permitting detachment of said clutch shaft endwise from the other shaft and relatively to said gripping means.

5. The combination of a main shaft and a detachable stop clutch shaft connected thereto for rotary movement therewith, clutch mechanism cooperating with said stop clutch shaft for stopping and starting the same, said clutch mechanism including a driving clutch member adapted to be connected to the shaft, a movable stop cooperating with said clutch mechanism to engage and disengage the clutch member and driving means, and means for permitting detachment of said stop clutch shaft endwise relatively to said clutch mechanism.

6. The combination of a main shaft and a stop clutch shaft connected thereto and adapted to be detached therefrom, means for transmitting power thereto and including clutch mechanism cooperating with said stop clutch shaft for stopping and starting the same, said clutch mechanism including a clutch member and shiftable gripping means located between the clutch member and shaft, and means for permitting detachment of said stop clutch shaft endwise relatively to said gripping means.

7. The combination of a pair of connected shafts located in alinement and one thereof comprising a detachable clutch shaft, clutch mechanism for starting and stopping said shafts and including a driving clutch member and a driven clutch member, shiftable gripping means cooperating with said mem-

- bers and located in recesses in said shaft, and means for permitting detachment of said shaft endwise from the other shaft and relatively to said gripping means.
- 5 8. The combination of a pair of connected shafts located in alinement and one thereof comprising a detachable clutch shaft, mechanism for starting and stopping said shafts, a machine frame for housing said clutch 70 shaft against access, and a detachable bushing carried by said frame at the end of said clutch shaft to permit access thereto whereby said shaft may be detached endwise from the frame and relatively to said clutch 75 mechanism.
- 10 9. The combination of a pair of connected shafts located in alinement and one thereof comprising a detachable clutch shaft, mechanism for starting and stopping said shafts, a machine frame for housing said clutch shaft against access, and removable means for permitting access to the end of said clutch shaft to permit the same to be drawn endwise from the frame relatively to said clutch 80 mechanism.
- 15 10. The combination of a machine frame, a rotary shaft, a detachable shaft connected in alinement to said shaft and housed within said frame, clutch mechanism for starting and stopping said shaft, and means removable from the outside of the frame for permitting access to the end of said detachable shaft, said detachable shaft being shiftable relatively to said clutch mechanism.
- 20 11. The combination of a main shaft and a stop clutch shaft connected thereto and adapted to be detached therefrom, clutch mechanism cooperating with said stop clutch shaft for stopping and starting the same, said clutch mechanism including a driven 85 clutch member, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member.
- 25 12. The combination of a main shaft and a stop clutch shaft connected thereto and adapted to be detached therefrom, clutch mechanism cooperating with said stop clutch shaft for stopping and starting the same, said clutch mechanism including a driven 90 clutch member adapted to be connected to a shaft, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member.
- 30 13. The combination of a main shaft and a stop clutch shaft connected thereto and adapted to be detached therefrom, means for transmitting power to said driving means, clutch mechanism cooperating with said 95 stop clutch shaft for stopping and starting the same, said clutch mechanism including a driven clutch member, a stop lever, a movable stop carried thereby and adapted to cooperate with said driven clutch member for engaging and disengaging the clutch mechanism, means for shifting said stop lever and stop into and out of operative position relative to the clutch mechanism, braking mechanism cooperating with said driven clutch member, and cushioning means carried by said stop lever and cooperating with said stop.
- 35 14. The combination of a main shaft and a stop clutch shaft connected thereto and adapted to be detached therefrom, clutch mechanism cooperating with said stop clutch shaft for stopping and starting the same, said clutch mechanism including a driven 100 clutch member, a stop lever, a movable stop carried thereby and adapted to cooperate with said driven clutch member for engaging and disengaging the clutch mechanism, means for shifting said stop lever and stop into and out of operative position relative to the clutch mechanism, braking mechanism cooperating with said driven clutch member and controlled by said stop lever, and cushioning means carried by said stop lever and cooperating with said stop.
- 40 15. The combination of a rotary shaft, a stop clutch shaft adapted to be connected thereto for rotary movement therewith, means for driving the same and including clutch mechanism cooperating with said stop 105 clutch shaft for stopping and starting said main shaft, said clutch mechanism including a driven clutch member, a swinging stop lever, a stop finger carried thereby and cooperating with said driven clutch member, braking mechanism cooperating with said driven clutch member, and means for limiting the movement of said braking mechanism independently of the movement of the stop lever.
- 45 16. The combination of a rotary shaft, a stop clutch shaft adapted to be connected thereto for rotary movement therewith, means for driving the same and including clutch mechanism cooperating with said stop 110 clutch shaft for stopping and starting said main shaft, said clutch mechanism including a driven clutch member, a swinging stop lever, a stop finger carried thereby and cooperating with said driven clutch member, braking mechanism cooperating with said driven clutch member and controlled by said stop lever, and means for limiting the movement of said braking mechanism independently of the movement of the stop lever.
- 50 17. The combination of a main shaft and a stop clutch shaft connected thereto and adapted to be detached therefrom, clutch mechanism cooperating with said stop clutch shaft for stopping and starting the same, said clutch mechanism including a driven 115 clutch member adapted to be connected to a shaft, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member.
- 55 18. The combination of a main shaft and a stop clutch shaft connected thereto and adapted to be detached therefrom, clutch mechanism cooperating with said stop clutch shaft for stopping and starting the same, said clutch mechanism including a driven 120 clutch member adapted to be connected to a shaft, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member.
- 60 19. The combination of a main shaft and a stop clutch shaft connected thereto and adapted to be detached therefrom, clutch mechanism cooperating with said stop clutch shaft for stopping and starting the same, said clutch mechanism including a driven 125 clutch member adapted to be connected to a shaft, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member and controlled by said stop lever, and means for limiting the movement of said braking mechanism independently of the movement of the stop lever.
- 65 20. The combination of a main shaft and a stop clutch shaft connected thereto and adapted to be detached therefrom, clutch mechanism cooperating with said stop clutch shaft for stopping and starting the same, said clutch mechanism including a driven clutch member, a stop lever, a movable stop carried thereby and adapted to cooperate with said driven clutch member for engaging and disengaging the clutch mechanism, means for shifting said stop lever and stop into and out of operative position relative to the clutch mechanism, and braking mechanism cooperating with said driven clutch member and controlled by said stop lever, and means for limiting the movement of said braking mechanism independently of the movement of the stop lever.

17. The combination of a rotary shaft, a stop clutch shaft adapted to be connected thereto for rotary movement therewith, said stop clutch shaft being shiftable relative to said main shaft for independently detaching the same, clutch mechanism cooperating with said stop clutch shaft for stopping and starting said main shaft, said clutch mechanism including a driven clutch member, 10 a swinging stop lever, a stop finger carried thereby and cooperating with said driven clutch member, braking mechanism cooperating with said driven clutch member, and means for limiting the movement of said braking mechanism independently of the movement of the stop lever.

18. The combination of a rotary shaft, a stop clutch shaft adapted to be connected thereto for rotary movement therewith, 20 clutch mechanism cooperating with said stop clutch shaft for stopping and starting said main shaft, said clutch mechanism including a driven clutch member, a swinging stop lever, a stop finger carried thereby and co- 25 operating with said driven clutch member, cushioning means carried by the stop lever and cooperating with said stop, braking mechanism cooperating with said driven clutch member, and means for limiting the 30 movement of said braking mechanism independently of the movement of the stop lever.

19. The combination of a rotary shaft, a stop clutch shaft adapted to be connected 35 thereto for rotary movement therewith, clutch mechanism cooperating with said stop clutch shaft for stopping and starting said main shaft, said clutch mechanism including a driven clutch member, a swinging stop 40 lever, a stop finger carried thereby and co-operating with said driven clutch member, braking mechanism cooperating with said driven clutch member and controlled by said stop lever, and means for limiting the movement of said braking mechanism independently of the movement of the stop lever, and comprising a member carried by said stop lever and cooperating with a part of said 45 braking mechanism for shifting the same, 50 said braking mechanism having a curved co-acting portion concentric with the axis of said stop lever.

20. The combination of a main driven shaft, a stop clutch shaft adapted to be connected thereto for rotary movement therewith, power transmitting means concentric with said stop clutch shaft, clutch mechanism cooperating with said stop clutch shaft for stopping and starting said main 60 shaft, said clutch mechanism comprising driving and driven clutch members, a swinging stop lever, a stop finger carried thereby and cooperating with said driven clutch member for engaging and disengaging the

same, braking mechanism cooperating with 65 said driven clutch member and controlled by said stop lever, and means for limiting the movement of said braking mechanism independently of the movement of the stop lever, and comprising a roller carried by said 70 stop lever and cooperating with a part of said braking mechanism for shifting the same, said braking mechanism having a curved co-acting portion concentric with the axis of said stop lever. 75

21. The combination of a machine frame, a rotary shaft, a detachable shaft connected in alignment thereto, mechanism for stopping and starting said shafts, bearings for said shafts carried by said frame, and means for permitting removal of said detachable shaft from the outside of the frame and relatively to said bearings. 80

22. The combination of a machine frame, a rotary shaft carried thereby, a detachable shaft section telescoped with said shaft and normally connected thereto for rotary movement, a bearing for said shaft section carried by the frame, and mechanism for starting and stopping said shaft, said shaft section being detachable from the outside of the frame by shifting the same relatively to said shaft and bearing. 85

23. The combination of a machine frame, a rotary shaft carried thereby, a detachable shaft section normally connected to one end of said shaft for rotary movement therewith, a detachable shaft section adapted to be connected to the opposite end of said shaft a hand wheel carried thereby, and means for causing said second shaft section to be normally disconnected from said shaft. 95

24. The combination of a rotary shaft comprising a pair of sections keyed together to permit shiftable movement of one section relatively to the other, means for transmitting power to the shaft and including stop clutch means cooperating therewith for stopping and starting the same, one of said shaft sections being shiftable endwise thru said clutch means to disconnect the shaft section. 105

25. The combination of a rotary shaft comprising a pair of telescopic sections keyed together, a driving wheel mounted on one of said sections, and clutch means between said driving wheel and last section, the latter being shiftable endwise relatively to the clutch means to detach the same. 115

26. The combination of a rotary shaft, means for transmitting power to said shaft and including stop clutch mechanism for stopping and starting the same, a movable stop lever adapted to cooperate with said clutch mechanism, and means for operating said stop lever, said means engaging said stop lever and having a movement therewith to operate the same and also having a prede- 120

terminated movement relatively to the stop lever without operating the same.

27. The combination of a rotary shaft, stop motion control means cooperating therewith for stopping and starting the same and comprising clutch mechanism, a stop lever and a stop finger carried thereby, all adapted to cooperate with said clutch mechanism, and means for operating said stop lever, said latter means comprising a member having a predetermined shiftable movement relative to said stop lever and having a part adapted to engage said stop lever for movement therewith.

15 28. The combination of a rotary shaft, mechanism for starting and stopping said shaft and including a swinging stop lever shiftable relatively to said shaft for controlling the starting and stopping of the shaft, 20 and means for swinging said stop lever and comprising a rod engageable with said lever and having a lost-motion connection therewith to cause the rod in its initial movement to shift relatively to the stop lever without 25 swinging the lever and in its subsequent movement to swing the stop lever relatively to the shaft.

29. The combination of a rotary shaft, stop clutch mechanism for starting and stopping the same and including a shiftable stop lever, a power transmitter for transmitting power to said shaft and including clutch means, treadle controlled means for operating said clutch means and having a lost motion connection with said stop lever for operating the lever subsequent to the operation of said clutch means.

30 30. The combination of a rotary shaft, stop mechanism for stopping and starting said shaft and including clutch mechanism cooperating with the shaft, a power transmitter having a driving connection with said shaft, said transmitter including a driving clutch member and a driven clutch member, and a common treadle operated means adapted to be shifted for engaging said clutch members and for operating said stop mechanism subsequent to the engagement of said clutch members.

50 31. The combination of a rotary shaft, a driving wheel carried thereby, clutch means for connecting said wheel to the shaft, stop mechanism cooperating with said clutch means, a power transmitter comprising a power driven wheel, a belt drive connecting said wheels, brake means for said power driven wheel, clutch mechanism for connecting said power driven wheel with a source of power, treadle means for operating said clutch mechanism, and means for adjusting said clutch mechanism independently of said treadle means to vary the speed at which said shaft starts to rotate.

60 32. The combination of a rotary shaft, clutch mechanism carried by said shaft for

stopping and starting the same, a shiftable operating member for said clutch mechanism, a power transmitter for transmitting power to said shaft and comprising a pair of clutch members, an operating member for said clutch members, and a common means for shifting each of said operating members, and for shifting said second named operating member prior to the other.

70 33. The combination of a rotary shaft, a clutch wheel thereon, clutch mechanism for connecting said wheel to the shaft, stop mechanism for operating said clutch mechanism, a power transmitter including a clutch wheel having a driving connection with said first clutch wheel, said transmitter also including clutch mechanism for connecting said second clutch wheel with a source of power, and a common treadle operated means for operating said second clutch mechanism.

75 34. The combination of a rotary shaft, a clutch wheel thereon, clutch mechanism for connecting said wheel to the shaft, stop mechanism for operating said clutch mechanism, a power transmitter including a clutch wheel having a driving connection with said first clutch wheel, said transmitter also including brake mechanism for said second named clutch wheel, a clutch for connecting said wheel with a source of power, and a common treadle means for operating said clutch and brake mechanism and also for operating said stop mechanism subsequent thereto.

90 35. The combination of a rotary shaft, stop clutch mechanism therefor and comprising a shiftable stop lever, a presser foot lifting lever, a shiftable operating member engageable with said stop lever for shifting the same and having means for shifting said lifting lever and a treadle for operating said member.

95 36. The combination of a rotary shaft, stop clutch mechanism therefor and comprising a shiftable stop lever, a presser foot lifting lever located above said stop lever, and a shiftable rod slidably engaging said stop lever to move relatively thereto at one time and to shift the same at another time, and a treadle for operating said rod, said rod having an extension located in position to operate said presser foot lifting lever.

100 37. The combination of a rotary shaft, a driving member carried thereby, clutch mechanism between said driving member and drive shaft, means for controlling said clutch mechanism, brake means for the shaft controlled by said last means and means for limiting the movement of said brake means independently of the movement of said last means.

38. The combination of a rotary shaft, stop clutch mechanism therefor and comprising a stop lever, brake means for said shaft, means carried by said stop lever for 5 operating said brake means, and a treadle operated member for shifting said stop lever and thereby said brake means, said member having a lost-motion connection with the stop lever to permit independent shifting 10 of the member without shifting the stop lever and brake means.

39. The combination of a rotary shaft, stop clutch mechanism therefor and comprising a stop lever, brake mechanism for 15 said rotary shaft, means for operating the brake mechanism from the stop lever and means for limiting the movement of the brake mechanism independently of the movement of the stop lever.

40. The combination of a rotary shaft, stop clutch mechanism therefor and comprising a stop lever, brake mechanism for 20 said rotary shaft, means for operating the brake mechanism from the stop lever and means for limiting the movement of the 25 brake mechanism independently of the movement of the stop lever, said latter means comprising cooperating members carried by

the brake mechanism and stop lever, one member having a part formed concentrically 30 with the pivotal axis of the stop lever.

41. The combination of a rotary shaft, clutch mechanism carried thereby for stopping and starting the same, a shiftable operating member for said clutch mechanism, brake mechanism for the shaft operated by said operating member, a power transmitter for transmitting power to said shaft and comprising a pair of clutch members, an operating member for said clutch 40 members, brake mechanism cooperating with one of said clutch members and controlled by said last operating member, and a common means for shifting said last operating member prior to the other.

42. The combination of a rotary shaft, clutch mechanism for starting and stopping the same, brake means for said shaft, a lever for controlling said brake means, and a treadle rod having a lost-motion connection with said lever to permit independent shiftable movement of the rod prior to the operation of said lever.

Signed at Nyack, New York, this 1st day of December, 1923.

JOHN P. WEIS.
